— Inventor

Thomas M. Larsen,
By his Attorneys Edgar Galt & Co

UNITED STATES PATENT OFFICE.

THOMAS M. LARSEN, OF BROOKLYN, NEW YORK.

DRAWING-MACHINE.

1,088,910.

Specification of Letters Patent. Patented Mar. 3, 1914.

Application filed March 6, 1913. Serial No. 752,264.

To all whom it may concern:

Be it known that I, THOMAS M. LARSEN, a citizen of the United States, and residing at Brooklyn, in the county of Kings and State of New York, have invented certain new and useful Improvements in Drawing-Machines, of which the following is a specification, such as will enable those skilled in the art to which it appertains to make and use the same.

This invention relates to machines for drawing patterns or curves for use in cutting sheet metal elbows, and the object thereof is to provide an improved machine of this class by means of which a sheet metal elbow of any desired angle may be cut and formed of two or more pieces as may be desired.

The invention is fully disclosed in the following specification of which the accompanying drawings form a part, in which the separate parts of my invention are designated by suitable reference characters in each of the views, and in which—

Figure 1 is a plan view of the central portion and operative parts of my machine; Fig. 2 a transverse central vertical sectional view on the line 2—2 of Fig. 1; Fig. 3 a front view of the central part of the machine looking in the direction of the arrow 3 of Fig. 2; Fig. 4 a sectional view on the line 4—4 of Fig. 2 and on an enlarged scale; Fig. 5 a section on the line 5—5 of Fig. 2 and on an enlarged scale, and Fig. 6 a section on the line 6—6 of Fig. 2 and on an enlarged scale.

In the practice of my invention I provide a frame comprising a base plate *a* of any suitable material and the opposite side portions of which are provided with upright supports *b* and *b*², the support *b*² being at the front of the machine. The base plate *a* is also provided, on its opposite side portions, and within the supports *b* and *b*² with longitudinal guides or tracks *c* and *c*² in which is placed a longitudinally movable sheet supporting board *d* provided at the right hand side edge thereof with a longitudinal gear *d*², and the gear *d*² acts as a straight edge to line a sheet of metal *d*³, on which the elbow sections are to be drawn when said sheet of metal is placed on the

board *d*, and the said sheet of metal may also be held on the said board by means of thumb tacks *d*⁴.

The support *b* is provided in the top portion thereof with a vertically movable bearing block *e*, and the support *b*² with a corresponding vertically movable bearing block *e*² of greater vertical dimensions than the bearing block *e*, and the position of these bearing blocks may be adjusted in the supports *b* and *b*² by means of a well known screw adjustment, as shown at *e*³, and said supports *b* and *b*² are each provided on their outer faces with a scale *b*³ only one of which is shown in Fig. 3, and by means of which the exact positions of the said bearing blocks may be regulated.

A shaft *f* is mounted transversely in the bearing blocks *e* and *e*² and provided at its front end with a crank *f*² and within the support *b*² with a large gear *f*³ which meshes with a smaller gear *f*⁴ on a stub shaft *f*⁵ mounted in the bottom part of the bearing block *e*², and the stub shaft *f*⁵ is provided with a gear *f*⁶ similar to the gear *f*³, and mounted in the bottom portion of the support *b*² is another stub shaft *g* provided with a gear *g*² similar to the gears *f*³ and *f*⁴, and the gear *g*² meshes with and operates in connection with the longitudinal gear *d*² on the board *d* for the purpose of moving said board longitudinally of the machine.

Mounted centrally or between, the supports *b* and *b*² are two guide rods *h* arranged in a horizontal plane, and these rods are supported at one end in the back support *b* and at the other in a yoke-shaped bracket *h*² connected with the support *b*².

Mounted on and movable longitudinally of the guide rods *h* is a block *i* the front end portion of which is provided with a central longitudinal slot *i*² in which is mounted a longitudinally movable block *i*³ having a depending tubular shell *i*⁴ provided at its lower end with a detachable head *i*⁵ having a set screw *i*⁶ and adapted to serve as a holder for a pencil or scribe *i*⁷, and within the shell *i*⁴ is placed a spring *i*⁸ which bears on the end of the pencil or scribe *i*⁷, and with this construction the position of said pencil or scribe in its holder may be ad-

justed as will be readily understood. The block i^3 which is movable longitudinally of the block i is provided with a screw i^9 having a thumb nut i^{10} and by means of which the position of the block i^3 in the block i may be adjusted and the pencil or scribe i^7 correspondingly adjusted. In the rear end portion of the block i and centrally thereof and between the guide rods h is secured a vertical pin j the upper end of which is screw threaded and provided with a nut j^2 ; but the pin j may be secured in the block i in any desired manner. The upper end of the pin j fits in a recess j^3 in the lower end of a plate k having a central longitudinal slot k^2 through which the shaft f passes, and passed through the end of the pin j is a lock pin j^4 by which the plate k is connected with the pin j and on which the plate k is free to turn or rock.

Mounted on the rear side of the plate k and having a sliding tongue and groove connection therewith is an oblong supporting plate m the top and bottom ends of which are provided with keepers m^2 in which is mounted a rotary disk n having a central oblong slot n^2 through which the shaft f passes, and said disk is connected with said shaft by means of a pin n^3 passed through said shaft and having a rotary bearing in the opposite side walls of the slot n^2 ; or said pin may be fixed in the disk n and have a rotary or other movement on the shaft f . On the rear side of the supporting plate m is a semi-circular scale plate or protractor o which is rigidly secured to the rotary disk n at o^2 , and this protractor is provided with a segmental slot o^3 , and a pin o^4 is passed through the shaft f and through the protractor o and provided with a thumb nut o^5 by means of which the protractor o may be adjusted into the desired position.

The protractor o is provided with a scale p representing degrees from zero to 90° , and the shaft f is cut out at p^2 to serve as a pointer in the adjustment of the protractor o , and with this construction and with the protractor o in the position shown in Fig. 2, the turning of the shaft f by the crank f^2 will result in moving the board d longitudinally of the machine and a straight line will be drawn on the sheet d^3 by the pencil or scribe i^7 , as shown at x , in Fig. 1, but if the protractor o be set at any degree between zero and 45° and the shaft f be turned the pencil or scribe i^7 will draw a curved line, as shown at x^2 in Fig. 1, the extent or radius of said curved line being determined by the degree at which the protractor o is set.

The exact method of procedure will be best understood by giving an example. Suppose that it is desired to form an elbow of 90° . It is first necessary to determine how

much extension the separate members of the elbow must have for the purpose of making the pipe connections, in order to determine at what distance the pencil or scribe i^7 is placed from the straight edge gear d^2 in beginning the operation of making the curve, and it will be understood that this point is fixed at the end of the board at which the curve is begun. With this point determined, if it is desired to make an elbow of 90° and consisting of two parts, the protractor o will be set at 45° , and with the board d at the limit of its movement to the right, the crank f^2 is turned and a curved line similar to x^2 will be drawn on the sheet d^3 , it being understood that the exact radius of this curved line would be such that when two sections of the sheet d^3 were thus marked out, said sheets folded and connected in the usual manner would produce an elbow of 90° . Suppose it is desired to make an elbow of more than two parts, the following rule is followed: If the elbow is to be composed of 10 parts, I multiply 10 by 2 and subtract 2 from the product which gives 18. This remainder is then divided into the desired angle of 90° which produces a quotient of 5° . The protractor will then be set at 5° , and 10 pieces may be marked out on the sheet or sheets d^3 in the manner hereinbefore described, and when said pieces are cut from said sheet they are connected in the usual manner to form an elbow of 90° composed of 10 parts.

It will be understood that the above rule is followed in all cases where it is desired to make an elbow of more than two parts and of an angle of any desired degree, said rule being briefly as follows: Multiply the number of sections by two, subtract two from the product, and divide the remainder into the angle of the elbow to be produced, and the result will determine where the protractor o is to be set.

In the accompanying drawings the gears f^3 , f^6 and g^2 are all of the same diameter, while the gear f^4 is one-half thereof in diameter, and in the use of this machine the diameter of the elbow to be made is twice the distance between the centers of the shaft f and the rods h , and this diameter may be increased or decreased by adjusting the bearing blocks e and e^2 and changing the guide wheel f^6 to suit said adjustment. The pin j has a rotary movement in the block i , and it will be understood that the protractor o is always locked to the shaft f by means of the thumb nut o^5 , and when the shaft f is turned the protractor o and the disk n both turn therewith, and this gives a gyrating movement to the plate k , and this results in the curve x^2 being drawn on the sheet d^3 . Any suitable marker may be substituted for the pencil or scribe i^7 , and my invention is not

limited to the use of the metal sheet d^3 , as the curves may be drawn on paper and transferred to a metal sheet if desired, and any suitable support for the block i may be substituted for the rods h , and other changes in and modifications of the construction herein described may be made, within the scope of the appended claims without departing from the spirit of my invention or sacrificing its advantages. The protractor o cannot be used beyond the angle of 45° , and the farthest said protractor can be turned through the shaft f in the direction of the arrow x^3 in the use of the machine, is indicated in Fig. 2 by the dotted line x^4 which indicates the position of the disk n when said protractor is set at 45° , and this is the degree at which the protractor is set in making an elbow of 90° and consisting of two parts. In making an elbow of more than two parts, the protractor must be set at less than 45° . In making an elbow of over 90° more than two parts are employed and the protractor must be set between zero and 45° , the particular degree at which it is set depending on the number of parts employed in the elbow.

Having fully described my invention, what I claim as new and desire to secure by Letters Patent is:—

1. In a machine of the class described, a frame comprising a base provided at its opposite sides with uprights, a sheet support movable longitudinally on said base, a transverse support arranged over the sheet support, a marker support movable longitudinally on said transverse support, a shaft mounted in said uprights and over said transverse support, and means whereby the turning of said shaft will move the sheet support longitudinally of the frame and the marker support transversely of the frame.

2. In a machine of the class described, a frame comprising a base having opposite side uprights, a sheet support movable longitudinally on said base, a transverse support mounted between said uprights, a marker holder movable longitudinally on said transverse support, a shaft mounted in the top portion of said uprights, a plate connected with the marker holder and provided with a central slot through which said shaft passes, a support connected with said plate, a rotary disk mounted on said support, a protractor connected with said disk and passing through said shaft, and means whereby the turning of said shaft will move the sheet support longitudinally of the frame.

3. In a machine of the class described, a frame comprising a base provided at its opposite sides with uprights, a transverse support mounted between said uprights, a marker holder movable longitudinally on

said transverse support, a sheet support movable longitudinally of the base, a shaft mounted in said uprights and over the transverse support, and means whereby the turning of said shaft will move the sheet support longitudinally of the base, a protractor mounted in the said shaft centrally thereof and adjustable therein into different positions, a plate connected with the marker holder by a universal joint and provided with a central slot through which the said shaft passes, a support connected with said plate and a disk connected with the protractor and rotatable in said support, said shaft being passed centrally through said support and said disk, and being loosely connected with said disk.

4. In a machine of the class described, a base, a sheet support movable longitudinally thereof, a marker holder supported above the base and movable transversely of the machine, a shaft mounted above the marker holder, and means whereby the turning of said shaft will move the sheet support longitudinally of the base and the marker holder transversely thereof.

5. In a machine of the class described, a frame, a marker holder movable transversely thereof, a shaft, a slotted plate connected with said marker holder by a universal joint and through which the shaft passes, a support connected with said plate, a rotatable disk connected with said support and provided with a large central opening through which the shaft passes, a protractor connected with said disk and passing through a central longitudinal slot in said shaft, and means for adjusting said protractor in said shaft.

6. In a machine of the class described, a frame comprising a base and upright side supports, a sheet support movable longitudinally of the base, a marker support, a holder mounted on said marker support and movable transversely of the base, a shaft mounted over the marker support and provided with vertically adjustable end bearings, a large gear wheel mounted on one end portion of said shaft, a stub shaft mounted in the bottom part of the corresponding bearing and having a small gear meshing with the gear on said shaft, and another gear mounted on said stub shaft and geared in connection with the sheet support, and means whereby the turning of said shaft will move the marker holder transversely of the machine.

7. In a machine of the class described, a sheet support movable longitudinally of the machine, a marker holder movable transversely of the machine, a main shaft mounted in the top portion of the machine and having vertically adjustable end bearings, one of said end bearings being provided in

the bottom part thereof with a stub shaft having a small gear meshing with a large gear on the main shaft, another gear on the stub shaft in operative connection with said sheet support, and means whereby the turning of said main shaft will move the marker holder transversely of the machine.

In testimony that I claim the foregoing

as my invention I have signed my name in presence of the subscribing witnesses this 10
4th day of March 1913.

THOMAS M. LARSEN.
